UNITED STATES PATENT OFFICE.

BENJAMIN WOLHAUPTER, OF NEW ROCHELLE, NEW YORK.

RAIL-ANCHOR.

1,345,428.

Specification of Letters Patent.

Patented July 6, 1920.

Application filed February 28, 1916, Serial No. 81,010. Renewed October 14, 1919. Serial No. 330,668.

To all whom it may concern:

Be it known that I, BENJAMIN WOLHAUPTER, a citizen of the United States, residing at New Rochelle, in the county of Westchester and State of New York, have invented certain new and useful Improvements in Rail-Anchors, of which the following is a specification.

This invention relates to a simple and practical form of rail anchor to prevent longitudinal creeping of railway rails. It has for its object the provision of a device of this character possessing means for effectually and firmly gripping the rail upon movement of the latter in a longitudinal direction, while at the same time being of a form that may be readily and economically manufactured by the ordinary forging machine process or otherwise.

10 A further object of the invention is to provide a rail anchor associated with a chair-plate, and combining therewith in a novel manner so that the anchor proper is most effectually maintained permanently in an operative position as long as the rail is seated upon the chair-plate. Also, the anchor proper is so constructed and arranged that it remains operative regardless of the expansion and contraction of the rails, and entirely obviates the employment of springs or equivalent auxiliary means to hold it in operative position.

20

The essential features of the invention involved in the general form of the anchor proper and its mounting on the chair-plate are susceptible of structural change without departing from the invention, but certain preferred and practical embodiments are shown in the accompanying drawings, in which—

Figure 1 is a top plan view of a rail anchor or anti-creeping device embodying the present invention, the rail being shown in dotted lines.

Fig. 2 is a vertical transverse sectional view on the line 2—2 of Fig. 1.

Fig. 3 is a plan view of a modification illustrating the rail clutching member in the form of a rail clip which embraces the rail flange and grips the top and bottom of the latter.

Fig. 4 is a transverse sectional view on the line 4—4 of Fig. 3.

Like references designate corresponding parts in the several figures of the drawings.

In carrying forward the invention there

is employed a chair-plate 1 upon which is seated the rail R and which is interposed between the latter and the top of the tie for the usual purposes. Aside from its function as a supporting and bearing plate for the rail, the chair or chair-plate houses and supports the rail anchor proper. This second function of the chair-plate is provided for by forming in the top thereof a housing chamber or recess 2, within which is freely mounted a reciprocating clutch-carrier designated by the numeral 3. In the preferred embodiments of the invention, the clutch-carrier preferably consists of an oscillating or swinging arm having a free back and forth or reciprocating movement horizontally over the floor of the housing chamber or recess 2, as will be clearly apparent from Figs. 1 and 3 of the drawings. The said arm is provided at one end with a downwardly projecting pivot stud or gudgeon 4 having a loose pivotal bearing in the bearing hole 5 formed in the chair-plate 1. At its free or swinging end the clutch-carrier 75 or arm 3 carries a rail-clutching member which may be of different types or forms of construction. In that shown in Figs. 1 and 2 of the drawings, the said rail-clutching member designated by the numeral 6 consists of an upstanding jaw projection integral or rigid with the swinging end of the arm 3 and provided upon its inner side with a curved, and preferably toothed, wedging face 7 which is adapted to be engaged with the edge of the rail flange in all positions of the clutch carrier or arm 3. From the construction described it will be observed that the chair-plate 1, which has the usual rail flange abutment shoulder 7', 90 and suitably arranged spiking holes 8, supports the rail anchor proper in such a manner that the seated rail holds it at all times in proper operative position with its pivot 4 engaged with the bearing hole 5, so that upon longitudinal movement or creeping of the rail in either direction, the free or swinging end of the clutch carrier will move with the rail. This movement of the swinging end of the clutch-carrier with the rail results in swinging the wedging face 7 farther inward toward the web of the rail and consequently into tight wedging engagement with the rail flange so that the two elements become interlocked and the rail held against further movement. In this connection it will be observed that in order to obtain an 100 105 110

effective leverage for the swinging or reciprocating clutch carrier the pivot thereof is located in a vertical plane at any point it may be found in practice to be most effective.

As already stated, the rail-clutching member at one end of the clutch carrier or arm 3 may be in different forms, and to illustrate the range of modification that may be resorted to for this part of the invention, reference is now made to Figs. 3 and 4 of the drawings. In these figures of the drawings the rail clutching member is in the form of a rail clip 8^a having upper and lower divergently related jaws 9 and 10 which, respectively, bind upon the top and bottom surfaces of the rail flange. The interval or socket 11 between the jaws 9 and 10 of the clip is of a tapering form corresponding to the taper of the rail flange in that an inward movement of the clip upon the rail flange will cause a tight clutching or gripping of the clip with the latter. The rail clip 8^a in the modified form of construction is loosely mounted upon the swinging or free end of the clutch carrier or arm 3. One convenient form of mounting for this purpose is shown in the drawings and consists of a holding pin 12 projecting upwardly from the swinging end of the arm 3 and loosely engaging in a play-slot 13 formed in the heel part 14 of the clip 8^a. This form of construction is quite effective for the purpose, as the clip 8^a will be crowded inward upon the rail flange when the rail moves in either direction and thereby swings the free end portion of the arm 3 therewith, resulting in shortening the distance between the free end of the said arm 40 and the edge of the rail flange.

Other forms of construction may be utilized and it will also be understood that changes in the form, proportion and minor details of construction may be used without departing from the spirit or sacrificing any of the advantages of the invention.

I claim—

1. A rail anchor comprising a chair having a rail flange abutment, and a clutch-carrier, one end of which carries a clutching member engaging the rail flange, the other end extending toward the rail flange abutment and pivoted in said chair.
2. A rail anchor comprising a chair carrying a rail flange abutment and a movable clutch-carrier, one end of the latter carrying a rail flange clutching member, and the opposite end pivoted in said chair between said member and said abutment.
3. A rail anchor comprising a support having a rail abutting shoulder, and a horizontally swinging arm carrying a rail clutching member at one end, and pivoted to the support at its opposite end between said member and the shoulder.

4. A rail anchor comprising a chair, having a rail flange abutting shoulder, and a clutch-carrier at one end pivotally connected with the chair adjacent to said shoulder and at the other end adapted to engage the rail flange.

5. A rail anchor comprising a chair, having a rail abutting shoulder, a reciprocating clutch-carrier, having a rail clutching member adapted to engage one rail flange and pivotally connected to the chair, whereby a longitudinal movement of the rail tends to force the rail flange against said abutment through a pulling movement of the clutch-carrier.

6. A rail anchor including in combination with the rail, a chair having a rail-supporting face provided with a clearance recess, said recess having the major portion thereof lying beneath the base of the rail, a clutch carrier mounted in said recess and having an upstanding rail engaging member at one end and means at the other end for pivotally engaging the chair.

7. A rail anchor including in combination with the rail, a chair having a rail supporting face provided with a clearance recess the major portion of which is covered by the base of the rail, a pivot opening at one end of said recess, an upstanding rail abutment on the chair, and a clutch carrier mounted in said recess and having rail flange engaging means at one end and means at the opposite end for entering the said pivot opening.

8. A rail anchor comprising a chair having a rail supporting face provided with a clearance recess, and a pivot opening, a clutch carrier mounted in said recess, and having reversely disposed projections at opposite ends, one of said projections adapted to engage the rail flange and the other adapted to fit in said pivot opening.

9. A rail anchor comprising a chair having a rail-supporting face provided with a housing chamber, a rail actuated clutch carrier arranged in said chamber and pivotally connected with the chair, said carrier having means at its free end for engaging the rail flange.

10. A rail anchor comprising a chair having a rail supporting face, a housing chamber having the major portion thereof located in the zone of the rail supporting face, and a clutch carrier arranged in said housing chamber and having one end thereof pivoted to the chair, the opposite end of said carrier having a rail engaging member.

11. A rail anchor comprising a chair having a rail flange abutment for engaging one side of the rail flange, a rail actuated clutch device having means for engaging the other flange of the rail, and also having an anchoring portion thereof extending toward the said abutment.

12. A rail anchor comprising a chair having a rail-supporting face, a rail flange abutment at one side of said face and projecting above the same, a rail actuated clutching device having the body thereof disposed in a plane beneath the rail-supporting surface, means carried by one end of said clutching device for projecting above the rail-supporting surface to engage the rail, and means at the other end of said device for engaging the rail chair.

13. A rail anchor including in combination with the rail, a chair for said rail having a recess, a rail actuated clutch device located in said recess beneath the rail and having one end thereof held in position by the rail, and the other end thereof exposed for engagement with the rail flange.

14. A rail anchor including in combination with the rail, a chair for the rail having a clearance recess substantially covered by the rail, a rail actuated clutch carrier located in the recess and having means at one

end for engaging the rail flange, and means at its other end for pivotally engaging the rail chair, said clutch carrier being held in the recess by the underside of the rail.

15. A rail anchor comprising a support, a movable carrier mounted on the support, and a rail-flange-embracing clip loosely connected with the carrier.

16. A rail anchor comprising a chair, a carrier arm pivoted at one end to the chair, and a rail-clutching member loosely connected with the opposite end of the carrier.

17. A rail anchor comprising a chair, a horizontally swinging carrier arm pivoted at one end to the chair, and a rail-flange-embracing clip having a loose pivotal mounting on the opposite end of the arm.

In testimony whereof I hereunto affix my signature in the presence of two witnesses.
